[57] ABSTRACT

An apparatus for the extraction of test samples from the dyeing vessel of a high pressure hank dyeing machine without the necessity of cooling or de-presurizing this vessel, comprises a unitary assembly of a mechanical or suction gripper device and a cutter to sever the strands retracted by the gripper device from a hank stationary in the vessel. The cutter may serve as a pressure seal between the interior of the vessel and a tubular housing of the gripper device serving to receive the cut strands.

SAMPLING APPARATUS FOR HIGH PRESSURE HANK DYEING MACHINES

This invention relates to a sampling apparatus, for high pressure hank dyeing machines, in which the sample is taken with the hank stationary. The term "hank" as used herein refers to any strand form of substrate, for instance textile fiber in rope or skein form.

The sampling, that is to say the removal of test dyeing samples from a hank, in a hank dyeing machine has hitherto involved evacuation of the interior of the kier or dyeing vessel, which is under pressure, after the machine has been stopped from an operating rate of the order of 140 - 180 m per minute.

In known methods of sampling the removal of the sample is done by hand and this requires the cooling down of the hank dyeing machine from its normal operating temperature, which is of the order of 125°C, to approximately 75°C, that is to say through about 50°C. Removal of samples by hand would otherwise be impossible. Having regard to the facts that the rate of cooling is about 1.5°C per minute, approximately 33 minutes are required for the cooling down. After this about 2 minutes are used in the sampling and then the machine must be brought up to the operating temperature again; one can reckon that the temperature rises by about 30°C per minute, which gives a time loss of 16 minutes. Thus the sampling requires an overall time of about 51 minutes.

Known forms of sampling apparatus for a high pressure hank dyeing machine are disposed outside the kier or dyeing vessel of the machine. The dye liquor circulates within the machine and at the same time through the sampling vessel. The hank circulates along with the dye liquor inside the machine, whilst the sample laps remain in the separate sampling vessel. The result of this is that often there may be deviations of about 10 percent in tone between the partially dyed hank and the sample which is later taken. This means that an exact analysis of the dyed condition of the hank is impossible.

One object of this invention is to provide a sampling apparatus which caters for an accurate evaluation of the dyeing.

Another object is a sampling apparatus which caters for the taking of a sample in a minimum of time and without closing the machine down.

In pursuance of these objects an improved sampling apparatus comprising a gripper device for engaging a part of said hank and a cutter device for severing the engaged part of said hank and separating from the remainder of the hank for inspection.

Advantageously the gripper device and the cutter device are assembled into a single structure and preferably the major part of this structure is installed in the interior of the dyeing vessel.

It is immaterial whether or where the sampling apparatus is applied to the machine but advantageously it will be arranged at the level of a hank entry port of the machine. It can be installed on or in new high pressure hank dyeing machines, or fitted to existing hank dyeing machines without any difficulty.

Various systems can be used to extract the test sample. Thus the gripper device can comprise a cylinder, tube or the like which can be evacuated of air and can be brought up to the hank or disposed adjacent the same to engage by a suction effect.

In other forms of the invention the gripper device may comprise a mechanically-operable gripper arm or a rod or the like with at least one hook or the like at the free end. This rod or the like may be a manually-operated spindle or push rod, which arrangement is particularly simple, not only to install but also to make, and in addition is inexpensive. The hooks provided on the spindle or rod may be of the kind for example which are used for angling; a type of anglers' hook could in fact be used. The hooks should be barbed so that they can be plunged into the stationary hank and will pull a part of this out when retracted or turned back.

The said cutter device can comprise at least one cutter blade which is movable transversely to the gripper device, being for example hydraulically or pneumatically operable. It may, for instance, be constituted by a pneumatic piston-cylinder unit which is double-acting or single-acting with a return spring.

In a preferred embodiment of the invention the gripper device is in the form of a spindle which is at least partially and displaceably mounted in a chamber which can be pressurized; this chamber may have a port, closed by a flap or the like, to allow for removal of the sample.

An example of embodiment of the invention is illustrated by way of example in longitudinal section in the accompanying drawing.

An extraction tube or sleeve 2 accommodating a push rod 3 is provided on the wall 1 of the kier of a high pressure hank dyeing machine. The tube 2 defines a chamber 4 the purpose of which will be described in detail below. The push rod 3 is provided with a handle 5 and is sealed by a sealing ring 6. The tube 2 is fitted with a head portion 7 and this carries a hand lever 8 and a setscrew 9. The tube 2 is provided laterally with a withdrawal opening (not shown) which can be airtightly closed by a cover. The free end 10 of rod 3 has two or more barbed hooks 11, the relevance of which will be explained below.

Welded at right angles to the tube unit 2 is a block 12 which accommodates a movable cutter device 13 slidable at right angles to the axis of the tube unit 2. This cutter device comprises a frame 14, a cutting blade 15, and an extension piece 16 of an operating device. Cutter device 13 is formed with an aperture 17 of a diameter approximately equal to that of the hollow interior of tube unit 2.

Block 12 also carries a pneumatic device for actuating cutter device 13. This comprises a piston unit 18 which cooperates with an abutment 19 on block 12.

The projected position of the actuating piston unit 18 is illustrated in dotted lines in the drawing. The piston unit, which has not been illustrated in detail, has a connecting conduit 20 leading to a duct 21 in tube unit 2. 22 designates the connection to a pressure source.

The supply of compressed air (from a source not shown) is controlled by means of the hand lever 8. Compressed air passes into the compression chamber (not shown) of piston unit 18 and brings the piston into the dotted position, that is to say into a position in which aperture 17 registers with chamber 4. At this instant the high pressure hank dyeing machine is, in the normal way, under pressure with the hank stationary, so that the same pressure will prevail in chamber 4. The push rod 3 is then pushed in so that hook 10 can engage part of the hank.

Push rod 3 is then withdrawn, whereafter the piston of unit 18 is brought into its other dead center position by means of a return spring (not shown), that is to say into a position in which the aperture 17 is moved towards the upper end of block 12. Blade 15 cuts off the part of the hank which has been drawn out by hook 11.

Not only is the pneumatic pressure which keeps the aperture in cutter blade 15 in register with chamber 4 interrupted when lever 8 is moved to enable the return spring described above to move the cutter blade into the position illustrated in full line, but air is vented from chamber 4 through an opening (not shown). In the position of the cutter blade 14 shown in full line, chamber 4 is separated from the compression area in the high pressure hank dyeing machine. The withdrawal flap (mentioned above but not illustrated) is now opened and the sample removed.

Use of the sampling apparatus according to the invention only requires two minutes. The cooling down and re-heating of the machine, previously necessary as mentioned above, is dispensed with.

It is also to be noted that the hank may for example be stopped with a seam located in the direct vicinity of an upper feed roller of the high pressure hank dyeing machine. Positioning can be controlled optically by using contrasting seams or markings in the hank. Alternatively an electronic detection and control, for example by means of a seam characterized by a metal thread, can be used.

The sample which is withdrawn using the apparatus according to the invention has exactly the same color tone as the remainder of the hank, especially as the hank does not have to remain stationary for long, nor does it have to remain stationary for a long period in the dye liquor.

I claim:

1. In a hank dyeing machine having a vessel through which at least one hank is moved during dyeing an improved sampling apparatus comprising a gripper device

40

for engaging a part of said hank and a cutter device for severing the engaged part of said hank and separating from the remainder of the hank for inspection.

2. Sampling apparatus according to claim 1, in which said gripper device and said cutter are combined in a unitary structure, and part at least of this structure is installed in the interior of said vessel.

3. Sampling apparatus according to claim 1, in which said gripper device comprises a movable mounted rod 10 having an operative free end provided with at least one hook for engaging said hank.

4. Sampling apparatus according to claim 3, in which said rod is mounted for movement in a housing defining a chamber which can communicate with the interior of said vessel.

5. Sampling apparatus according to claim 4, in which said housing has a port for withdrawal of a sample severed from said hank, and a flap for closing said port.

6. Sampling apparatus according to claim 1, in which said cutter device comprises guide means, at least one cutter blade mounted in said guide means, and means for moving said cutter blade in said guide means transversely to said gripper device.

7. Sampling apparatus according to claim 6, in which fluid pressure means are used for moving said cutter blade.

8. Sampling apparatus according to claim 1, comprising a sampling tube mounted in a wall of said vessel and projecting into the interior thereof, a manually-operable gripper rod displaceably mounted in said tube and having hook means at the inner end thereof, a cutter slideway secured to the end of said tube within said vessel, a cutter slide mounted in said slideway and comprising a frame with an apertured cutter blade secured therein, and pneumatic means for moving said cutter slide transversely of said rod to sever hank material retracted by the same and to bring the aperture in said cutter blade into and out of register with the interior of said tube.
